WORK HOLDER FOR FORGING MACHINES

Stanley J. Snorek, Berwyn, Ill., assignor to Western Electric Company, Incorporated, a corporation of New York

Application March 5, 1948, Serial No. 13,155

3 Claims. (Cl. 78—6)

1

This invention relates to apparatus for forming indentations in articles and more particularly to an apparatus for pressing pairs of opposed conical shaped recesses of the same size in opposite sides of relay armatures.

An object of the present invention is to provide a simple and effective apparatus for forming indentations in an article.

In one embodiment of the invention, there is provided a support for supporting an article between a pair of opposed tools mounted for reciprocation on opposite sides of the support and positively actuated in opposite directions by fluid actuators operated under control of suitable control mechanism. The article is positioned on the horizontal surface of the support with one edge in engagement with a stationary jaw on the support and is clamped against the stationary jaw by a horizontally movable clamping jaw yieldably mounted for movement on a plunger moved under the influence of a third fluid actuator. The third fluid actuator, in response to the admission of fluid pressure therein under control of a pair of manually operated valves, advances the plunger and the movable jaw to effect the clamping of the article against the stationary jaw, and the end of the plunger, as it is moved forward, actuates a bell crank clamping member to clamp the article vertically against the horizontal surface of the support. A micro-switch, operated in response to the forward movement of the plunger, actuates the control mechanism to admit fluid under low pressure to the tool actuators to cause the forward movement of the tools into engagement with the opposite surfaces of the article, after which a foot valve may be actuated to admit fluid under high pressure to the tool actuators to cause the tools to be further advanced to press identical indentations in opposite sides of the article.

The invention will be more fully understood by the following detailed description thereof and the accompanying drawings illustrating a preferred embodiment of the invention in which

Fig. 1 is a plan view of a portion of the apparatus:

Fig. 2 is an enlarged vertical lateral sectional view taken on the line 2—2 of Fig. 1;

Fig. 4 is a central longitudinal vertical sectional view of the apparatus taken on the line 4-4 of Fig. 1 and showing the parts of the apparatus in normal inoperative position;

2

Fig. 5 is a view similar to Fig. 4 showing an article clamped in position thereon;

Fig. 6 is an enlarged face view of a portion of the article showing the indentations formed therein by this apparatus;

Fig. 7 is an enlarged fragmentary view of a portion of the indentation forming tool; and

Fig. 8 is a diagrammatic view of the apparatus showing the control system thereof.

10 The apparatus disclosed herein is adapted to simultaneously press a pair of oppositely disposed conical recesses or indentations into an article 10. The article 10, in the embodiment shown herein, is a relay armature comprising a 15 flat iron disc having a rectangularly shaped tab extending therefrom into the opposite edge portions of which it is desired to form conical shaped pivot bearing recesses 11. The recesses 11, instead of being formed directly in the soft iron 20 armature, are formed in hardened inserts 12 secured to the armature and forming a part thereof.

The article 10 is adapted to be placed on a horizontal surface or seat 15 of a work support 25 or block 16 (Figs. 2 and 5) mounted on a base plate 17 of the apparatus. An upwardly and transversely extending shoulder or jaw 18 is formed on the forward end of the support 16 and is adapted to be engaged by the tab portion 30 of the article. The article 10 may be clamped against the jaw 18 by a movable jaw 19, which has a reduced forward end slidably engaging the surface 15 and a vertical V-shaped surface 20 engageable with the edge of the article 10. The jaw 19 is yieldably mounted on an actuating rod 35 or plunger 22 for movement therewith and is provided with a longitudinal aperture 23 for receiving the rod 22. The plunger 22 is connected at one end to a piston of a fluid actuator 40 24 and is guided at its forward end in a bore 25 in the support 16. A collar or shoulder 26 is provided on the rod and serves as a stop engageable with the shoulder formed by the reduced end of the aperture 23. A spring 27 encircling 45 the rod 22 is interposed between the shoulder 26 and a bushing 28 slidably engaging the rod and threaded into the forward end of the aperture 23 and acts to urge the jaw 19 forwardly against the stop shoulder 26 and maintain the jaw in its forward position on the rod 22.

50 jaw in its forward position on the rod 22. A clamping member 30 operable in response to the forward movement of the actuating rod 22 is provided to clamp the article 10 vertically against the surface 15 of the support 16. The 55 member 30, comprising a bell crank having a de-

pendent arm 31 and a laterally extending arm 32, is fulcrumed on a pin 33 mounted in a block 34. The block 34, which is mounted on the base 17 of the apparatus, is recessed to receive a portion of the clamping member 30 and has a recess 35 for receiving one end of a compression spring 36, the other end of which fits into a recess in the arm 32 and urges the bell crank clamping member 30 in a clockwise direction. The arm 32 of the clamping member 30 is recessed at 38 to receive a block 39, which is pivotally mounted on a pin 40 carried by the clamping member 30. The clamping member 30 is urged by the spring 36 to its inoperative position, as shown in Fig. 4, and is adapted to be rotated in a counter-clockwise direction by the forward movement of the actuating rod 22 to clamp the article 10 between the lower surface of the block 39 and the surface 15 of the support 16, as shown in Fig. 5.

Disposed on opposite sides of the work support 16 and slidable in suitable guide blocks 45-46 (Figs. 1 and 2) are a pair of oppositely disposed tool actuating rods or carriers 47-48. The rods 47 and 48 are connected to pistons of fluid actuators 50 and 51, respectively, which are mounted on the base 17 of the apparatus. Each of the tool carriers 47 and 48, at its forward end, is recessed to receive a tool holder 54 in which the tool 55 is mounted. The tool 55 has a conical end 56 and a flat annular shoulder 57 around the pointed end 56. The shoulder 57 is engageable with the side of the article 10 to press or flatten the annular ridge formed by the end 56 during the indentation forming operation. The shoulder 57 also serves to stop the forward movement of the tool and gage the size of the indentation, which otherwise would be determined by the pressure applied to the tools.

The fluid actuators 50 and 51 (Fig. 8) comprise air cylinders of the same size having reciprocable pistons therein which are positively driven in opposite directions by air under pressure admitted through pairs of conduits or pipe lines 69, 61 and 62, 63 connected to ports at the inner and outer ends, respectively, of the air cylinders 50 and 51. The lines 69 and 61 are connected at a point equidistant from the cylinders to an air supply line 65, which has connected therein a speed control valve 66, a solenoid operated cutoff and bleeder valve 67, check valve 68, and a pressure regulating valve 69 set to provide a low pressure in the line 65. The valve 69 is connected through a line 71 to the main high pressure air supply line 72. The lines 62 and 63 are connected at a point equidistant from the cylinder to a branch supply line 73, which has in it a speed control valve 78, a solenoid operated cutoff and bleeder valve 77, and a pressure regulating valve 73 set to provide a high pressure in line 75. By having the fluid actuators 50 and 51 of the same size and applying fluid thereto through the arrangement of piping disclosed, equal pressures are applied to the pistons thereof and to the tools actuated thereby.

A branch conduit 80 connects the high pressure regulating valve 78 to the main supply line 72. Another branch line 81 connected to the main supply line 72 supplies air to the air cylinder 24 and has in it a pair of manually operated control valves 83 and 84 and a speed control valve 85. A foot operated control valve 87 is connected by a line 88 between the high pressure line 77 and the low pressure line 65 and serves, when operated, to pass the high pressure air from the line 75 through the lines 88, 65, 60 and 61 to the air cylinders 50 and 51.

The check valve 68 is set to pass the air therethrough in the direction of the arrow and prevent the flow of air therethrough in a reverse direction. The speed control valves 66 and 76 are set to pass therethrough, at a predetermined rate, air exhausted from the cylinders 50 and 51 and thus regulate the rate of movement of the tool carriers 47 and 48. Air passing through the valves 66 and 76 in a forward direction to the cylinders 50 and 51 is not affected by the valves 67 and 76. The solenoid operated cut-off and bleeder valves 67 and 77 are spring-returned to normal operative position and solenoid actuated to their other operative position. Each of the valves 67 and 77, in its normal operative position, cuts off the bleeder ports therein and establishes communication between the lines connected to it and, in its other operative position, cuts off communication between the lines connected to it and establishes connection between the bleeder ports in the valve and the line connected to the fluid actuator.

The solenoid operated valves 67 and 76 are connected in electrical circuits to microswitches 90 and 92, respectively, (Fig. 8) and when either switch is actuated, the circuit associated therewith is closed to energize the solenoid connected therein and shift the valve to its other operative position. The microswitch 92 (Figs. 4 and 5), mounted on the block 16, is adapted to be actuated by a cam 94 carried by the rod 22 in response to the reciprocation of the rod. As indicated in Figs. 4 and 5, the switch 92 is actuated or closed when the actuating rod 22 is in its retracted position and is open when the rod 22 is in its advanced position. The switch 90 (Figs. 4 and 5) is mounted on the block 34 and is adapted to be actuated by a plunger 96 mounted for horizontal reciprocation in the block 34 and normally urged to the left, as viewed in Figs. 4 and 5 by a spring 97. The plunger 96 is moved to the right to actuate and close the switch 90 by the movement of the bell crank clamping member 30 in response to the final portion of the forward movement of the actuating rod 22.

In the normal or inoperative condition of the apparatus, as indicated in Fig. 8, the microswitch 92 is actuated, the circuit associated therewith is closed, and the solenoid valve 77 is actuated to its second position, cutting off the bleeder ports of the valve and establishing communication between the high pressure air supply and the inner ends of the air cylinders 50 and 51. The microswitch 90, in the normal inoperative position of the apparatus, is in its open position, and the solenoid operated valve 67 is in its normal or deenergized position, cutting off the low pressure air supply to the outer ends of the air cylinders 50 and 51, and effecting communication between the bleeder ports of the valve 67 and the outer ends of the cylinders 50 and 51. The tools and the pistons connected thereto are thus in their retracted position, being moved into and held in this position by the high pressure air admitted to the inner ends of the cylinders 50 and 51 while the air from the outer ends of the cylinders has been exhausted through the bleeder ports of the valve 67.

Operation

In the operation of the mechanism, an article 10 is placed on the surface 15 of the work support 16 with the rectangular tab portion of the article in engagement with the jaw 18 of the work support, after which the operator engages the control valves 83 and 84 with his hands and actuates them to admit fluid pressure into the end of

the air cylinder 24 to advance the rod 22. As the rod 22 advances, it moves the jaw 19 into engagement with the edge of the article 10 to yieldingly clamp it against the stationary jaw 18 and as the rod 22 continues to advance, the forward end thereof will engage and actuate the bell crank clamping member 30 to clamp the article 10 against the surface 15 of the work support.

During the first portion of the movement of the actuating rod 22, the cam 94 thereon will disengage itself from and open the microswitch 92 and thereby open the circuit to and deenergize the solenoid valve 77 and effect its movement to its normal operating position to cut off the high pressure air supply to the lines 62 and 63 and the inner ends of the pistons 50 and 51 and, simultaneously therewith, establish communication between the inner ends of the cylinders 50 and 51 and the bleeder ports in the valve 77.

As the actuating rod 22 continues its forward movement, the microswitch 90 will be actuated thereby through the agency of the arm 32 and plunger 96. With the actuation of the microswitch 90, the circuit is closed to energize the valve 67 and move it to its other operative position, connecting the low pressure air supply to the lines 60 and 61 and the outer ends of the air cylinders 50 and 51 and cutting off the communication between the outer ends of the cylinders and the bleeder ports in the valve 67. Thus, with the valve 67 moved to its other position under the influence of the energization of the solenoid, low pressure air flows into the outer end of the air cylinders 50 and 51 and moves the pistons and tools forward at a predetermined rate of movement, controlled by the valve 66, into engagement with the article 10. The movement of the tools is arrested when the ends thereof engage the article 10 because of the low pressure of the fluid urging the tools 55 forward and this insures that both of the tools will be in proper starting position and in engagement with the article even though the location of the articles 10 in the work holder may vary slightly in succeeding operations.

The operator may now step on the foot control valve 87 to connect the high pressure air to the lines 65, 60 and 61 and to the outer end of the cylinders 50 and 51. The high pressure air, which is the same in the air cylinders 50 and 51, causes the tools to be advanced simultaneously and at the same rate of travel to press the conical ends 56 thereof into the sides of the article to form identical conical shaped indentations 12 therein. As the conical ends 56 of the tools are pressed into the sides of the article, the metal in the article will be displaced and tend to form an outwardly extending annular bead which will be engaged by the shoulder 57 on the tool and substantially flattened or pressed back into the article, after which further movement of the tools is arrested by the engagement of the shoulders 57 with the sides of the article.

After the indentations 12 have been completely formed, the operator may release the control valves 83, 84 and 87. With the air pressure cut off from the air cylinder 24, the piston and the rod 22 are returned to their normal retracted position by the spring 100 in the air cylinder. As the rod 22 moves to its retracted position, it effects the opening of the microswitch 92 and the deenergization of the valve 67, which is then moved to its normal operating position to cut off the low pressure air supply to the outer ends of the cylinders and establish communication

between the outer ends of the cylinder and the bleeder ports of the valve. As the actuator rod 22 continues its return movement, the microswitch 92 is actuated to effect the movement of the solenoid operated valve 77 to its energized position to reestablish communication between the high pressure air supply and the inner ends of the air cylinders 50 and 51. The pistons in the cylinders 50 and 51 and the tools actuated thereby will thus be moved to their retracted positions at a rate of travel governed by the speed control valve 66 and thereby complete the cycle of operation.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A device for holding an article in a predetermined position in an article processing apparatus comprising a support having a flat surface engageable with one face of said article for supporting the article thereon, a stationary jaw on said support engageable with one side of said article for positioning said article in one direction on said support, an actuating member mounted for reciprocation on said support, a movable jaw, means yieldably mounting said movable jaw on said actuating member for movement therewith in a predetermined path toward said stationary jaw to yieldably clamp said article on said support against the stationary jaw, a bell crank, means supporting said bell crank for rocking movement with one arm thereof in the path of movement of said actuating member for actuation thereby and the other arm of the bell crank above said flat surface, said bell crank being rocked in one direction in response to movement of said actuating member in one direction to cause said other arm of said bell crank to engage an article on said support and clamp it against said support, and means for reciprocating said actuating member.

2. A centering and holding device comprising a support having a seat engageable with one face of an article to be processed for supporting the article thereon, a stationary jaw on said support engageable with one side of said article and adapted to limit the movement of the article in one direction to a predetermined position, an actuating member mounted for reciprocable movement on said support, a movable jaw having a recess therein for receiving a portion of said article to position said article along a predetermined center line, means yieldably mounting said movable jaw on said actuating member for movement therewith toward said stationary jaw to yieldably clamp said article against the stationary jaw and on said predetermined center line, a bell crank, means mounting said bell crank for pivotal movement with one arm thereof in the path of movement of said actuating member for actuation thereby and the other arm thereof guided for movement toward and away from said seat to clamp an article against said support in response to movement of the actuating member in one direction, and means for actuating said actuating member.

3. A device for holding an article in a predetermined position in a machine for processing said article comprising a support having a seat engageable with said article for supporting said

article thereon, a stationary jaw on said support engageable with one side of said article, a jaw movable toward said stationary jaw and having article engaging surfaces forming a V-shaped recess for positioning said article on a predetermined center line and clamping said article against said stationary jaw, a bell crank, means mounting said bell crank for pivotal movement and for guiding one arm thereof toward and away from said seat, a clamping element pivotally mounted on said one arm of said bell crank engageable with an article on said seat, a rod mounted for reciprocal movement along a predetermined path and engageable with the other arm of said bell crank for rocking said bell crank, means yieldably mounting said movable jaw on said rod for movement therewith toward and away from said stationary jaw, and actuating means for reciprocating said rod to cause the actuation of said movable jaw and said bell 20.

crank for effecting the centering and clamping of said article by the movable jaw against the stationary jaw and the clamping of said article against the seat by the clamping element.
